ELECTRICAL DISCHARGE DEVICE

Charles Spaeth, Flushing, N. Y., assignor to
Ne-Arga Corporation, Jersey City, N. J., a cor-
poration of New York

Application October 23, 1930. Serial No. 490,648

1 Claim. (Cl. 176—125)

This application is a continuation in part of my copending application Serial No. 343,873, filed March 2, 1929.

The invention relates to electrical discharge devices, particularly to devices used for purposes of illumination.

It is an object of the present invention to provide an electrical discharge tube which is capable of producing a very efficient white light.

10 Another object is to provide an electrical discharge illuminating tube wherein the color characteristics of the emitted light may readily be modified in a predetermined manner or be maintained constant at any desired value.

15 A further object is the provision of an electrical discharge tube operating at high efficiency and adapted to produce a concentrated brilliant light emission approximating sunlight.

In accordance with my invention a radiant 20 energy emitting discharge device is constructed having a filling of gas at reduced pressure and a plurality of electrodes for conducting an electrical discharge therethrough. For modifying the light emission from the device auxiliary 25 means are arranged to add to the gas filling in the desired amounts an agent for modifying the radiation spectrum. This auxiliary device is preferably in the form of a mercury reservoir provided with means for liberating mercury vapor.

30 A preferred form of my invention for illuminating purposes comprises an envelope containing an atmosphere of rare gas, such as neon, and having a reservoir of mercury. Electrodes are provided for passing a discharge directly through 35 the rare gas and another electrode for causing a discharge to be passed to the mercury in order to vaporize it. In order to secure the desired characteristics of illumination from the device means, such as resistances, inductances or capacitances 40 may be provided for controlling the relative intensities of the discharges. For liberating the mercury suitable heating means may be employed in place of the auxiliary electrode. This heating means may comprise any suitable source of external heat, but preferably is in the form of a heating coil placed adjacent to the mercury reservoir and adapted to be energized by the discharge current.

When it is desired to secure a white light approximating that of sunlight the filling of the envelope may be of neon gas used in conjunction with a reservoir or other means for supplying an exactly proportioned amount of mercury vapor. It is advisable where the tube is to be operated over a relatively long period of time to

maintain the mercury vaporizing means in operation at the correct intensity during the entire operation of the device. It is, however, possible to start the discharge through the rare gas column and then supply the necessary quantity of 60 mercury vapor for a short period of time, after which the device will continue to emit a white light for some time. As operation is continued the mercury is cleaned up, apparently either by condensation, occlusion, absorption, or some 65 other phenomena and the light emitted by the device gradually reverts to the characteristic color of the rare gas, which, in the case of neon, is substantially red. By operating the mercury vaporizing device at the correct intensity, mercury vapor is supplied at the same rate at which 70 it is used up and hence the color of the emitted light remains constant.

For producing other colors of light other monatomic gases, for example, helium, argon, xenon, 75 or krypton, may be used with mercury vapor, or one of a mixture of the rare gases of a given characteristic color emission may be used in conjunction with the means for liberating the vapor.

Other objects and advantages and the manner 80 of attaining them will be made clear in the following specification and accompanying drawing.

In the drawing, Fig. 1 shows a device constructed in accordance with my invention wherein the modification of the emitted spectrum is obtained 85 by the passage of a discharge to a spectrum modifying material; and

Fig. 2 shows a device wherein the cathode is of the oxide coated indirectly heated type.

Referring more particularly to the drawing, 90 Fig. 1 illustrates an electrical discharge tube comprising a light transmitting envelope 1 filled with rare gas, such as neon, and having a pair of main discharge electrodes 2 and 3 of any well-known type, having the usual lead-in wires. The 95 pressure of the gaseous atmosphere may range anywhere from .1 to 50 millimeters, but I find it preferable to use a pressure in the neighborhood of 6 millimeters. A reservoir for a quantity of mercury 4 is provided in the form of an appendix 100 5. For energizing the tube the main electrodes 2 and 3 are connected across a suitable source of current 14 by means of conductors 6 and 7. The source 13 may be of either direct or alternating current of a suitable high potential. 105 Connected in series with the conductor 6 is an adjustable resistance 8. For causing discharge to pass to the mercury 4 a connection 9 is made between a lead-in wire 59 sealed through the wall of the reservoir 5 and making contact with the 110

mercury, and the conductor 6. In series with the conductor 9 is an adjustable resistance 10.

During the construction of the device a quantity of alkali metal is introduced into the tube 5 envelope adjacent to the cathode 3. This alkali metal may, for example, be distilled into the envelope in the well-known manner, so that a film 3^a is formed on the inside of the wall thereof, or a small quantity of it may be put in, in solid 10 form. It is preferable, for best operation, that this deposit of alkali metal form a contact with the cathode 3 or its lead-in wires. The metal used may be sodium, potassium, rubidium, caesium or an alloy of these metals. For commercial 15 purposes potassium may be used alone to save expense.

This alkali metal is very important to the prolonged operation of the tube as it appears to function as a clean-up agent for excess mercury within 20 the main body of the tube. When a tube is used having no alkali metal it turns entirely blue after a relatively short period of operation and can not be restored to its original mercury free color. During the operation of the discharge device a 25 minute amount of mercury vapor is continuously generated by the auxiliary electrode and carried over into the main body of the tube, where it is excited by the main discharge current. When the exciting current is cut off this mercury vapor 30 remains in the main tube and apparently forms an amalgam or other association with the alkali metal, of such character that the mercury is not liberated during future operation of the device. This action is particularly effective where the 35 alkali metal is electrically connected to the cathode. Without the alkali metal the mercury vapor relatively quickly reaches such density in the main tube that only blue light is generated.

In operation, a current is caused to pass from 40 the source 13 between the two electrodes 2 and 3, thereby energizing the filling of rare gas and causing it to emit light having certain color characteristics. For example, where the rare gas is neon, the light will be predominantly red. In 45 order to modify these color characteristics the resistance 10 is adjusted so that a discharge passes between the electrode 3 and mercury 4, thereby causing a quantity of the mercury to be vaporized. The mercury vapor diffuses through the 50 gas in the envelope 1, emitting light rays of its characteristic blue color. By properly adjusting the resistance 10 it is possible so to balance the blue rays emitted against the characteristic color of the rare gas as to produce a light emission of any desired color. For example, where 55 the rare gas is neon, a proper adjustment of the resistance 10 may be made to cause the emission of white light, the blue rays of the mercury being complementary to the red rays of the neon. The resistances 8 and 10 serve also as ballast resistances for balancing the negative resistance 60 of the gaseous discharge path. These resistances should therefore never be cut entirely out of circuit, as the discharge current would increase to an excessive value. While the mercury reservoir is illustrated as positioned near to one of the main electrodes, it need not necessarily be so located. The device will likewise be operative with the 65 reservoir at other positions. By placing the

reservoir as shown, the impedance of its discharge path is made relatively large.

Fig. 2 shows a tube similar to that of Fig. 1, with the exception that the cathode is of the well-known indirectly heated oxide coated type. 80 I find that a suitable electrode may comprise a thin cylinder 33 of nickel coated with an oxide of barium, strontium or calcium. This cylinder may be heated by a resistance coil 34 energized by a heating transformer 35, the secondary of which 85 is provided with an adjustable tap 36 by which the neutral point may be determined.

The deposit of alkali metal 3^a is used in this modification the same as in the structure of Fig. 1 and precautions should be taken to prevent the metal from being vaporized by the heat of the cathode and carried out of electrical contact therewith. The lead-in wires 3^b and 3^c, may for example, be made long so as to space the cathode and heater far enough from the alkali metal to 90 prevent vaporization thereof.

It is well known that ordinary light tubes utilizing a filling of rare gas are adapted to operate at only relatively low current densities and that in order to secure life long enough for commercial 100 purposes it has been thought necessary to utilize electrodes operating at relatively low current densities. A device constructed in accordance with my invention will, on the contrary, operate at extremely high current densities without excessive 105 heating and without excessive deterioration.

Where neon gas and an auxiliary mercury electrode are used, as set forth, the color may be adjusted from the characteristic neon color, through white, to the characteristic mercury color. The 110 efficiency of tubes constructed in accordance with my invention is extremely high. For example, when using neon gas with mercury vapor to produce a white light, the amount of energy consumed is only about 0.20 watt per spherical candlepower. Because of this relatively high efficiency the amount of heat generated by the device is correspondingly small.

Lamps of this type are substantially silent in 115 operation, especially when direct current is used. They are therefore of great value where a white, 120 silent and relatively cool, high intensity illuminating source is desired, as in the recording of synchronized sound pictures.

It will be obvious to those skilled in the art that 125 the invention is capable of a wide variety of modifications and adaptations and that the present disclosure is intended merely to illustrate its nature without limiting its scope which is set forth in the appended claim.

What I claim is:

An electrical lamp comprising a container, a quantity of rare gas within said container, an anode at one end of the container and a heater type cathode within and at the other end of said 135 container, a reservoir attached to said container for storing small quantities of mercury, means for vaporizing a quantity of said mercury to modify the color of the light radiated from said rare gas, and a deposit of alkali metal within said container electrically connected to said cathode but spaced therefrom to prevent vaporization by heat generated by the cathode and to remove mercury vapor from the light column.
